FIG. 8

Inventor
Louis H. Anderson

33, Herbert E. Smith
Attorney

UNITED STATES PATENT OFFICE.

LOUIS H. ANDERSON, OF SPRINGDALE, WASHINGTON, ASSIGNOR OF ONE-HALF TO
HENRY LEETSCH, OF SPRINGDALE, WASHINGTON.

GATE.

Application filed May 11, 1925. Serial No. 29,391.

My present invention relates to improvements in gates adapted for use on farms, and of the type having a multiple movement whereby the gate is lifted or tilted on a horizontal pivot and then by influence of gravity is given a bodily movement in a horizontal direction, transverse of the roadway.

Two tilttable supporting tracks or suspending rails are employed for suspending the gate in closed or open positions, and means utilized in connection with the tracks or overhead suspending rails are employed for causing the necessary vertical lifting or tilting of the gate and its subsequent horizontal sliding or rolling movement to open or closed position.

The gate is operated through the instrumentality of a single cable having its ends extended a suitable distance along the roadway in order that one end may be pulled to open the gate, and after passing through the opening the driver may pull the other end of the rope to close the gate behind him.

The invention consists in certain novel combinations and arrangements of parts involving the use of mechanism actuated by the pull cable as will hereinafter be more fully pointed out and claimed.

In the accompanying drawings I have illustrated one complete example of the physical embodiment of my invention wherein the parts are combined and arranged in accordance with the best mode I have thus far devised for the practical application of the principles of my invention.

Figure 1 is a view in elevation showing the gate closed in full lines and indicated by dotted lines in tilted position and also indicated by dotted lines in open position.

Figure 2 is an enlarged detail view showing the right end of the gate latched in open position.

Figure 3 is a sectional detail view of one of the tubular pivoted track rails upon which the gate may be suspended.

Figure 4 is an enlarged detail view of the operating mechanism for tilting the suspending track rails and shifting the movement of parts for reverse action.

Figure 5 is an edge view of the mechanism of Figure 4.

Figure 6 is a rear elevation of the track rail connections.

Figure 7 is a detail view of one of the

lifting pulleys showing a portion of a cable thereon and stop devices on the cable and pulley bracket.

Figure 8 is an enlarged detail plan view of the operating mechanism with some parts omitted for convenience of illustration.

Figure 9 is a detail perspective view of the shifting device.

In carrying out my invention I utilize a central main post 1 located at one side of the roadway and in line with the fence posts 2 and 3 at the left and right in Figure 1, which latter posts form part of the fence 4. A small gate 5 is indicated at one side for use by pedestrians.

The gate is of suitable construction and preferably made up of two posts 6 and 7 that are connected by a frame work of palings and rails indicated at 8.

Extending above the ends of the gate posts are hangers or suspending bars 9 and 10 rigidly attached to the posts and provided at their upper ends with suitable rollers 11.

Through the instrumentality of the hangers or suspending bars and their rollers the gate is suspended from both of the track rails 12 and 13, which are of tubular construction, and supported in elevated position on their pivots 14 and 15 which pivots are supported between metal plates A and B secured at the top of the main post 1. The track-rails are normally disposed in horizontal position and are sufficiently elevated in order that a loaded team may pass through the gate opening when the track-rail 12, is elevated to shift the gate. The lower sides of the track-rails are fashioned with spaced flanges 16 to accommodate the rollers and their hangers, and the outer or remote ends of the track-rails are fashioned with stop lugs 17 to prevent displacement of the gate.

The roller of the hanger or suspending bar 9 is normally located in and travels the length of the tubular rail 12 and the roller of the suspending bar 10 is normally located in and travels the length of the tubular rail 13. Thus it will be apparent that the rail 12 may be tilted as indicated in dotted lines Figure 1 to swing the gate on the roller 105 in the tubular track 13 as a center, and when thus tilted the gate is free to run under influence of gravity to the right in Figure 1. As thus arranged, one end of the tilted gate is supported by a roller that is adapted to 110

run down the inclined track rail toward the main gate post while the other roller runs along its horizontally disposed track rail. In closing the gate the track rail, as 5 13, which was formerly disposed in the horizontal plane is tilted and the track rail 12 (which has returned to horizontal position) remains in that position, for the gate to roll to closed position as indicated in full 10 lines in Figure 1.

At its opposite ends the gate carries latches 18 and 19 fixed to the respective posts 6 and 7 for co-action with the latch pins 20 on fence post 2 and 21 on fence post 3. The 15 latches have cam faces 20' which ride over the latch pins as they contact therewith and then hook over the pins as indicated in Figure 2 to latch the gate. The gate is unlatched as it is lifted in its tilting movement, the initial upward movement disengaging the latch from the pin so that the gate is then free to be lifted and to roll down the inclined track rail.

Each of the track rails is provided with a 20 lifting arm as 22 and 23, and these arms are adjustable as to their length by use of a turn buckle 24 on each arm. The arms are disposed diagonally at the sides of the main post with their lower spaced ends pivoted 25 as at 25 to the respective track rails. At their upper ends these diagonally extending arms or tilting bars 22 and 23 are pivoted to the respective bell crank levers 27 and 26 which levers are pivoted at 28 and 29 on the 30 plate B. The bell crank levers are pivoted to the tilting arms at 30, and as best seen in Figure 6 one arm of each of the bell crank levers is pivoted to a vertically disposed link as 31 and 32 which is spaced at 35 the sides of the vertical center of the plate B. These links are draw links adapted to be pulled down to swing the bell crank levers and through the bell crank levers and tilting arms or bars 22, 23 tilt the track rails. 40 At their lower ends the links have studs 33 and 34 projecting laterally therefrom and extending through spaced, parallel, slots 35 and 36 in the plate B. Means are provided for alternate engagement with these studs 45 for depressing them to accomplish the tilting movement of the gate.

For operating the gate a single cable 37 is employed which is extended at both sides of the gate alongside the roadway and passes 50 under and around a pair of spaced guide pulleys 38 and 39 with their axes disposed transversely of the roadway. A stop or detent 40 is provided on the cable spaced sufficiently from the two pulleys so that it may 55 engage an abutment 41 on the bracket 42 which supports each pulley. There are two stops on the cable in order that only a predetermined pull may be made in either direction from one of the handles 43 at the ends 60 of the cable.

The cable is passed over and suspended from a guide pulley 44 rotatable on a stud shaft 45 which is fixed to and projects laterally from an oscillatable, vertically slidable actuating plate 46 which is supported on 70 plate B by means of a flanged housing 46'. This housing as seen in Figure 8 flares toward its lower end to permit oscillation of the slidable actuating plate.

As best seen in Figure 9 the actuating 75 plate or plunger 46 carries a loose cam arm 47 having a longitudinally extending central slot 48 through which the stud shaft 45 passes, so that while the cam arm moves with the plunger 46 the arm also is capable of 80 relative movement on the plunger. At its upper end the cam arm is fashioned in the form of an arrow head with cam faces 49 and 50 extending from its longitudinal center, and the lower end of the cam arm is connected to a pivoted reversing or shifting cam plate 51. By pivoting the cam arm to the cam plate at 52, the cam plate, which is pivoted at 52' to the plunger, performs the 85 functions of a crank arm between the plunger and the cam plate in the reversing movement of the operative mechanism.

A pull on a cable end causes one of the stops on the cable to engage an abutment 41, then a continued pull on the cable causes 90 the cable to depress the plunger through its pressure on the guide pulley 44. At its lower end the plunger is provided with side notches or shoulders 53 and 54 which are alternately adapted to co-act and engage with 95 the stud pins 33 and 34 of the links 31 and 32. In Figure 8 the oscillatable plunger 46 has been swung to position with its notch 53 engaging the stud 33 and as the plunger is pushed down through the action of the 100 cable, the link 31 will be made to swing the bell crank lever 26 to lift the track rail 13 through the tilting bar 23 for the purpose of closing the gate.

If the oscillatable plunger 46 is swung to 110 the left in Figure 8, the duplex actuating mechanism will be operated to tilt the track rail 12 through the described connections.

After a track rail has been tilted, as for 115 opening the gate, and the gate has rolled to open position, the cable handle 43 is released as the gate assumes its open position and upon release of the cable the weight of the uplifted track rail from which the gate has passed causes the said track rail to swing 120 down to horizontal position and through the bell crank, link and stud on the link the plunger is lifted again to normal raised position in Figure 6.

As the plunger descends the cam plate 125 51 through its cam edge 51' contacts with the stud 33 or 34 which is inoperative and the cam plate is swung on its pivot 52' to swing the oscillatable cam arm 47 on its pivot shaft 45 to a reverse position. 130

At the sides of the plunger are a pair of oppositely disposed shifting levers 56 and 57 pivoted at 58 on the plate B at the sides of the plunger and provided with lugs 59 and 60 respectively to alternately engage opposite sides of the lower end of the plunger.

A shifting lever is swung on its pivot to cause its lug to oscillate or swing the plunger on its pivot 45.

10 For coaction with the cam faces 49 and 50 of the cam arm 47 a cam roller 61 is carried by a weighted oscillatable bar 62 pivoted at 63 on the plate B above the plunger and to swing laterally as indicated in Figure 4 so that the roller may be engaged by one of the cam faces to swing the weighted arm on its pivot.

20 The arm carries weights 64 of sufficient capacity to give it a quick falling movement after the cam arm has started the swinging movement of the weighted arm or bar, in order that the weighted bar may strike a blow against either of the lugs or abutments 65 and 66 on the upper ends of the shifting 25 levers 56 and 57.

From this description it will be apparent that as the plunger descends, through the actuation of the cam plate 51 the cam arm 47 is swung on its pivot, say to the right in Figure 4. Then when the uplifted track rail descends to normal horizontal position, the plunger is automatically lifted. The roller 61 is now in the path of movement of the cam face 50 of the cam arm. When said face contacts with the roller the weighted bar is swung to the right as in full lines. The weighted bar contacts with abutment 66 of shift lever 57 and the lever is swung to its indicated position. The lower end of 40 the lever or its lug is engaged with the lower end of the plunger and the latter is swung or oscillated slightly to the left in its indicated position with notch 53 engaging the stud 34. The weighted bar now holds the 45 plunger in this operative position for the next pull on the cable, which will be in direction reverse to the first pull, for opening the gate.

Having thus fully described my invention, 50 what I claim as new and desire to secure by Letters Patent is—

1. The combination with a post, a pair of track rails pivoted thereon, and a gravity actuated gate suspended on said rails, of a slotted plate on the post, a pair of tilting arms pivoted to said rails, a pair of bell crank levers pivoted on said plate and pivotally connected to said tilting arms, a link on each lever having a stud guided in 55 said slotted plate, and means adapted to depress said studs alternately.

2. The combination with a tiltable gate and actuating means therefor, of operating means comprising a plunger for co-action

with the actuating means, a pair of guide pulleys and a single cable, means on the plunger for suspending the cable between said pulleys, and stop devices to resist pull on the cable to impart pressure for actuating the plunger.

3. The combination with a tiltable gate and actuating means therefor, of means comprising a plunger for co-action with the actuating means, a pair of guide pulleys and supports each having an abutment 70 thereon, a single cable on said pulleys and stops on said cable for co-action with said abutments, a suspending pulley on the plunger for said cable whereby the plunger may be depressed by a pull on the cable, and means for elevating said plunger.

4. The combination with a pair of tiltable track rails and duplex tilting means therefor, of operating means comprising a shiftable plunger and means for shifting said 85 plunger for alternate co-action with said tilting means, a pair of guide pulleys, a single cable, a pulley on the plunger for suspending the cable between the guide pulleys, and means for resisting the pull on 90 the cable in either direction to cause a depression of the plunger.

5. In a gate operating mechanism the combination with a plunger having a notched lower edge and actuating means 95 having studs for alternate engagement by said notched edge, means for depressing the plunger, and means for shifting the plunger for alternate engagement with said studs.

6. In a gate operating mechanism the combination with a compressible plunger and actuating means therefor, of a supporting housing in which the plunger is oscillatable, a pair of laterally spaced shifting levers for alternate co-action with said plunger, 100 means for shifting the levers, and means for actuating the shifting means.

7. In a gate operating mechanism the combination with a housing of an oscillatable plunger therein and actuating means for 110 the plunger, a pair of laterally spaced shifting levers for alternate co-action with the oscillatable plunger, a weighted, pivoted bar for alternate co-action with said levers, and means carried by the plunger for shifting 115 said weighted bar.

8. In a gate operating mechanism the combination with a housing of an oscillatable plunger therein and means for depressing the plunger, a pair of laterally spaced 120 shifting levers for alternate co-action with the oscillatable plunger, a weighted pivoted bar for alternate co-action with said levers, an oscillatable cam arm carried by the plunger for shifting said bar, and means for 125 shifting said cam arm.

In testimony whereof I affix my signature,
LOUIS H. ANDERSON.
